CLAIM

The ornamental design for a water tap, as shown and described.

DESCRIPTION

FIG. 1 is a front, right, and top perspective view of a water tap, showing my design.

FIG. 2 is a rear, left, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof; and,

FIG. 9 is a partial enlarged view of an area labeled 9 in FIG. 1 comprising a part of net.

The broken lines shown in the drawings are included for the purpose of illustrating portions of the water tap that form no part of the claimed design.

The dash-dot broken lines depict the boundaries of the enlargements that form no part of the claimed design.

1 Claim, 9 Drawing Sheets
